UNITED STATES PATENT OFFICE

2,608,829

PORTABLE MARINE FOUNDATION

Richard P. Knapp, Toledo, Ohio, assignor, by
mesne assignments, to Standard Oil Develop-
ment Company, Elizabeth, N. J., a corporation
of Delaware

Application March 30, 1948, Serial No. 17,903

1 Claim. (Cl. 61—46)

1

The present invention is concerned with an improved movable marine foundation. The invention is especially concerned with an apparatus for drilling oil wells in marine locations and submerged lands which will provide a firm, stable base for the drilling operations and which can be readily transported by floating from one location to another. The invention is more particularly directed to marine foundations adapted to be utilized in conjunction with barge drilling operations. In accordance with the present invention the barge containing conventional rig type drilling equipment is stabilized on the ocean floor employing portable marine pontoons which may be separate from the barge itself or which may actually comprise an integral part of a multiple section barge.

It is known in the art to utilize barges in moving well drilling rigs from location to location for marine drilling operations. However, the use of the present conventional type drilling barge has been limited to operations in water no deeper than the maximum depth of the barge hull. This limitation is caused by the lack of positive stability when the barge is submerged to the deck level. In operations of this character, it is absolutely essential that the barge have the utmost stability in order to avoid loss of the barge and the entire drilling equipment. At the present time there are several factors, among others, which control the extent to which drilling operations can be conducted under water. In the first place, the present barges can only be submerged to a limited extent. This is due to the fact that as the barge is submerged, the stability of the barge is decreased. For safety factors, it is necessary that this barge stability not go below a certain minimum value. In general, it can be stated that the stability of the submersible drilling barge is a function of the water plane area. Thus the stability of a conventional drilling barge completely disappears upon 100% submersion due to the fact that the water plane area becomes 0. That is to say, the stability becomes negative as the deck is submerged and the water plane area disappears.

An improved barge unit which consists of portable sections and which may comprise an integral part of the barge has been discovered. By utilizing the improved barge of the present invention, it is possible to operate in much deeper water than has heretofore been the case. Furthermore, by employing the present invention, greater stability and safety will be secured. By employing the present invention, it is possible to completely submerge the drilling barge and maintain the desired stability by utilizing therewith the pontoon

2

foundation elements. These submersible pontoon foundation elements provide the necessary water plane area to give the desired safety factor of stability in the positioning of the barge at the location desired. By employing the barge of the present invention, it is possible to positively control the rate of submersion and the rate of floating.

The invention may be more readily understood 10 by reference to the drawings illustrating various embodiments of the same. Figs. 1, 2, 3, 4, 5, 6 and 7 illustrate the invention wherein adjustable floating sections comprise sections of the multiple barge unit.

15 Referring specifically to Fig. 1 which illustrates an adaptation of the invention wherein the floating sections comprise an integral part of a multiple barge section, a working platform 20 and rig 21 are extended above the barge deck level 22 at a height determined by the maximum depth of water and wave amplitude at the operating site. The end sections 23 and 24 are affixed to the center section 22 in such a manner that they can be rotated 90° about an axis perpendicular to the 20 longitudinal center line of the structure and are of the proper geometrical shape to permit locking in either the horizontal or vertical position. When the end sections 23 and 24 are locked in the horizontal position as illustrated in Fig. 1, the 25 structure is a sea-going vessel and can be readily towed to any desired deep water location.

20 Fig. 2 illustrates the operation of the barge unit shown in Fig. 1. Similar numbers are used in Fig. 2 to designate the identical elements of 30 Fig. 1.

25 Referring specifically to Fig. 2, the end sections 23 and 24 are locked in the vertical position and the structure is ready for lowering to the ocean floor. With proper ballasting, the details of which are well known, the submersible hull can be safely submerged to any depth of water that is within the limits of the vertical height of the end sections 23 and 24. During the 30 sinking operation stability is provided by the end sections 23 and 24. These sections must have an adequate water plane area to insure positive stability and be of a height greater than the depths of the water in which the rig is to be positioned.

35 Fig. 3 is an end view of the barge in position on the ocean or marine floor. Elements similar to those of Fig. 1 are designated by the same numbers.

40 After the unit is landed on the marine floor, the 45 entire structure is leveled by ballasting the end sections. For example, in a preferred adaptation 50 of the invention, this positioning of the

pontoons is assisted by artificial scouring produced by fluid jets located at the lower limits of the end section. These jets are shown as 25 in Fig. 3. It is to be understood that any number of jets may be utilized and that air or water may be ejected to secure the desired scouring. Minor adjustments to level the platform may be accomplished by changing the length of platform supports. When a satisfactory position of the structure has been obtained, ballast is added or removed to keep the total weight on the bottom within the limits of the safe load carrying capacity of the ocean floor in that area.

Fig. 4 illustrates the operation of the invention in the refloating step. The structure is floated by the proper removal of ballast from areas 23 and 24 and 22 after that section reaches the surface to produce a uniform positive buoyant force. Jet action is preferably used to help free the end sections by scouring earthen material away from the bearing area. After reaching the surface, the section 22 may be lifted clear of the water if desired to clear a completed well or other surface obstruction. With the center section 22 afloat 15 the end sections 23 and 24 are rotated as described by ballasting or jacking into the horizontal position and the structure is ready to be moved to another location.

A very desirable method of refloating the unit is to employ jacking elements 30, illustrated in Fig. 4. The section 22 is raised at a controlled rate by the action of jacks in pontoon elements 23 and 24. This is very desirable since in raising the submersible barge, great care must be exercised. In general, it is absolutely necessary that this unit have a neutral or slightly negative buoyancy.

If the unit should at any time have a positive buoyancy, the barge would rise rapidly and probably would have either a translation or rotation movement or a combination of these. When it is considered that the derrick may be from about 150 to 250 feet above the barge, it is quite evident that this movement would cause the derrick to buckle and rupture. In other words, rotation with a radius of this magnitude will cause transverse forces of great magnitude which a conventional derrick structure can not withstand. Thus, it is absolutely essential that the buoyancy be a controlled buoyancy.

Furthermore, by employing a modification of the invention as illustrated in Fig. 4, the jack elements 30 can position barge element 22 at any point with respect to pontoon elements 23 and 24. Thus, the distance between the marine floor bottom and the element 22 can be regulated to a depth so that the working platform is positioned at any predetermined distance above the surface water in order to avoid wave action and the like.

Figures 5, 6 and 7 illustrate one method of operating the pontoon elements. Identical numbers are used to illustrate similar parts in Figures 5, 6 and 7. Barge element 30 has attached thereto as an integral part, pontoon element 31 which is L-shaped in design. When it is desired to move the multiple barge unit, water or other ballast is pumped into the vertical section of the pontoon causing it to revolve counter-clockwise about pivot 33.

The invention broadly contemplates the use of buoyant complementary sections to be used in connection with barge operations. These sections may be either attached or be free of the barge main section carrying the working plat-

10 form and the rig. By employing the invention as pointed out heretofore, it is possible to operate the barge section carrying the working platform and the rig at appreciably greater water depth.

When the barge is submerged and resting on the ocean floor, this structure will be subjected to minor forces of wave action as the greatest portion of the buoyancy compartments are located far below the surface with only the platform supports and the upper limits of the end sections in the area of destructive wave action. The working platform is installed at a height sufficient to clear the waves of maximum amplitude.

15 The platform supports and end sections can have any desired design or geometrical form to reduce wave action. The barge sections will have the necessary proportions in order to keep the center section at a depth below the surface where wave action is small or substantially non-existent.

The end sections can be made longer for operations in deeper water and the basic structure is so designed for operation in the minimum depth of water anticipated and thus will permit operation in limited range of depths above the minimum.

An additional desired feature of the invention is that under certain circumstances it may be possible to float the center section of the barge containing the working platform independent of the end sections providing it is found that these end sections cannot be readily broken loose. The center section and the end sections 20 can be manufactured so that this center section can be detached from the end sections. Thus, as the center section is floated, the end sections may serve as guides as the center section rises. The center section can then be removed from the area and the end sections broken loose by any desired or suitable means. After the end sections have been freed from the ocean floor these sections can then be reattached to the barge and the entire unit moved to the desired new location.

40 Having described the invention, it is claimed: 25 Marine foundation comprising a structure consisting of an adjustably buoyant hull supporting a working platform, a plurality of hollow pontoon members pivotally fixed to said structure, means to maintain said pontoon members in a first non-vertical position and a second vertical position, said hollow pontoon members being characterized by being trapezoidal in vertical cross-section, said pontoon members being further characterized by a length greater than the depth of the water in which the marine foundation is to be used, whereby on pivoting said members to the vertical position and on decreasing the buoyancy of the hull, the said members support the working platform above the water level.
